(57) CLAIM

The ornamental design for a “personal weighing scale,” as shown and described.

DESCRIPTION

FIG. 1 is a perspective view of a personal weighing scale in accordance with an exemplary embodiment of my new design, with a height indicator in an extended position;

FIG. 2 is a front elevation thereof;

FIG. 3 is a rear elevation thereof;

FIG. 4 is a left side elevation view thereof;

FIG. 5 is a right side elevation view thereof;

FIG. 6 is a top plan view thereof;

FIG. 7 is a perspective view of the personal weighing scale in accordance with my new design, with the height indicator shown in a retracted position;

FIG. 8 is a front elevation view thereof;

FIG. 9 is a rear elevation view thereof;

FIG. 10 is a left side elevation thereof;

FIG. 11 is a right side elevation thereof; and,

FIG. 12 is a top plan view thereof.
